UNITED STATES PATENT OFFICE

2,595,920

DEGREASING MACHINE

Otto J. Bratz, Adrian, Mich., assignor to American
Chain & Cable Company, Inc., Bridgeport,
Conn., a corporation of New York

Application April 5, 1944, Serial No. 529,875

2 Claims. (Cl. 134—107)

1

This invention relates to a machine for degreasing the interior and exterior of conduits or casings for push-pull assemblies of the Bowden type.

The main object of this invention is the provision of mechanism for degreasing and draining casings of Bowden wire.

Other objects of the invention will be apparent from the following description taken in connection with the drawings, in which:

Fig. 1 is a side view of a machine constructed in accordance with this invention;

Fig. 2 is a top plan view of a section of the machine;

Fig. 3 is a side view of a valve operating mechanism;

Fig. 4 is a transverse cross section on the line 4—4 of Fig. 1; and

Fig. 5 is a detail view showing the step of passing a conduit or casing into a burnishing case.

The machine shown in Figs. 1 and 2 as a preferred embodiment of this invention comprises a main lower solvent supply tank A, an auxiliary pump tank B connected on one side of the supply tank, an upper solvent heating tank C, inclined work support and degreasing and draining troughs D and an inclined burnishing case E.

The main solvent supply tank A is suitably supported on standards 6 and may be of rectangular shape, as disclosed, and near its bottom may be provided with a ledge 7 on which is supported a filtering screen 8. The inside of this tank, at a point below the screen, is in communication with the pump tank B, as indicated at 9.

Mounted in the upper end of the pump tank B is a pump 12 of any suitable description by means of which the solvent is delivered to the solvent heating tank C through piping 13 to which is connected a branch pipe 14 for delivering the solvent to the upper end of the burnishing case E. The pipe 14 may include a connection 15 so as to permit the right hand end of the pipe to be disconnected from the section of the pipe supported on the supply tank B.

The solvent in the heating tank C is heated by a suitable immersion type electric heater 16 of any well known construction which may be controlled to heat the solvent to the desired temperature.

The trough D is a double-decked construction comprising an upper open work tray portion 17 (Figs. 1, 2 and 4) and two lower closed degreasing and draining troughs 18 and 19 which extend through an opening in an end wall of the main supply tank A and a reinforcing plate, as shown in Figs. 1 and 2. The work tray 17 abuts the

2

reinforcing plate which, as well as this end wall of the main supply tank A, is provided with a hole 20 of just sufficient size to permit casings 21 (Figs. 4 and 5) to be passed from the work tray through the main supply tank A into the burnishing case E.

The solvent heating tank C is supported on suitable standards 23 (Figs. 1 and 2) on which is also supported the upper end of the double decked trough D so as to support the trough in an inclined position at an angle of about 7°. Communication is established between the solvent heating tank C and the degreasing and draining troughs 18 and 19 through tubes 24 and 25 (see also Fig. 3), controlled by a valve mechanism which comprises valves 26 and 27 supported on a bar 28 mounted on a shaft 29 suitably journaled in a wall of the tank C and provided at its outer end with an operating bar 28'. The shaft 29 may be rocked so as to open either valve and close the other by means of a cable 30 which has its ends connected to the ends of the operating bar 28' and which is supported on pulleys 31 and 32 supported on the trough D, as indicated in Figs. 1 and 2, so as to present a stretch of cable on each side of the trough for the convenience of the operator.

The lower end of the burnishing case E (Figs. 1 and 5) is supported by a tube 35 supported in the right hand end wall of the main supply tank A at a point above the screen 8 and extends into the tank a suitable distance, as indicated. The upper end of the burnishing case is supported in a bracket 36 on a standard 37 which supports the motor 38 and which is made extensible and adjustable, as indicated at 39, and includes pivoted parts, as indicated at 40, to support the motor at the proper height and angle.

The burnishing element consists of a twisted square wire 45 (Figs. 1 and 5) extending throughout the length of the burnishing case E and beyond it into the tank A to facilitate passing the casing or conduit 21 over the burnishing wire and into the burnishing case E, as is obvious especially from Fig. 5. Any suitable chuck 46 may be provided to transmit rotation from the motor to the burnishing wire 45.

This machine may be used for burnishing and degreasing any type of tube but it has been especially designed for burnishing the inside of coiled wire casings of the type disclosed in detail in Fig. 5 and which are used as the conduits or casings for push-pull devices of the Bowden wire type. These casings may be equipped with end fittings 50, as disclosed in Fig. 5.

The direction of twist of the burnishing wire

45 is such with relation to the direction of the rotation of the motor that the twisted square wire will act as a screw to force the solvent and the small particles of material loosened by the burnishing operation, down into the main supply tank A. In order that every section of the inside of the tube may be burnished the free end section of the wire is slightly kinked, as disclosed at 52 in Fig. 5.

The inside of the main supply tank A may be 10 lined near its upper end with a condensing coil 55 which may be connected at its upper end 56 with a suitable water supply and at its lower end 57 to the sewer. This condensing coil is provided to condense fumes that may rise from the 15 warm solvent in the tank A.

The machine is also provided with a hood, not disclosed, suspended above the main supply tank A to catch any fumes that may rise from the tank, and with a mild operating fan to withdraw 20 the fumes which, if desired, may be collected and condensed and returned to the tank A.

In operating the machine the work tray 17 is filled with conduits or casings to be burnished and degreased. The pump and heater are set in 25 operation and the valves 26 and 27 are adjusted so that the heated solvent will be delivered to the degreasing and draining trough into which the burnished casings are passed.

The casings in the work tray are passed manu- 30 ally one at a time through the opening 20 and through the main supply tank A into the burnishing case E and are then immediately withdrawn from the burnishing case and passed through the tank A into the selected trough 18 or 35 19. This operation is continued until the selected trough is filled with casings, after which the valve mechanism is adjusted so that the heated solvent will flow down through the other trough, which will then be filled with burnished 40 casings. While the latter trough is being filled, the casings in the other trough will drain and they will be ready for removal from the machine by the time said latter trough has been filled with casings.

While a preferred embodiment has been de-

5 scribed with particularity for purposes of disclosure, it is obvious that other embodiments may be constructed in accordance with the principles of this invention and within the scope of the claims.

I claim:

1. In a machine of the character described, the combination of a solvent supply tank, two inclined degreasing troughs draining into said tank, a solvent heating tank supplying heated solvent to said degreasing troughs, a pump for pumping solvent from said supply tank to said heating tank and valve mechanism for controlling the delivery of heated solvent to said troughs one at a time and to either desired.

2. In a machine of the character described, a double decked trough construction comprising an upper open work supporting trough, two lower degreasing and draining troughs located under said work support trough, a solvent supply tank for supplying solvent to said latter troughs and valve mechanism for controlling the delivery of solvent to said latter troughs, one at a time and to either desired.

OTTO J. BRATZ.
